JAMES SCHOFIELD, OF WORCESTER, MASSACHUSETTS, ASSIGNOR TO HIMSELF AND OSGOOD PLUMMER, OF SAME PLACE.

Letters Patent No. 61,767, dated February 5, 1867.

IMPROVEMENT IN LOOMS.

The Schedule referred to in these Letters Patent and making part of the same.

KNOW ALL MEN BY THESE PRESENTS:

That I, JAMES SCHOFIELD, of the city and county of Worcester, and Commonwealth of Massachusetts, have invented certain new and useful Improvements in Looms; and I do hereby declare that the following is a full, clear, and exact description of the same, reference being had to the accompanying drawing, forming a part of this specification, and which drawing represents an end view of so much of a power-loom as is necessary to illustrate my invention.

My improvements relate to the mode of operating the harnesses so that all the harnesses will be raised and lowered to bring the threads in each harness upon the same angle as the threads in the other harnesses when in the same position. That is to say, when the harnesses are operated to divide the warp-threads for the passage of the shuttle, all the threads above the shuttle, or in the upper shed, will be upon the same angle, and all below the shuttle, or in the lower shed, will be upon the same angle. (See red lines in the drawing.)

In the drawing, A represents the end piece of a loom for weaving fancy goods, and consequently requiring a number of harnesses. Only two of the back harnesses and two of the front harnesses are shown in the drawing, they being sufficient to illustrate my invention. The harnesses are operated by horizontal jacks, B, which are fulcrumed in the ordinary manner under the harnesses, as shown at a. The ends projecting in are connected to the harnesses in the usual manner, while the ends which project out are connected by wires or chains to the lower ends of the notched operating-bars C C, the latter being made and operated by the pattern-wheel D in the usual manner. E is the elevating rod, which works up and down in bearings, b b, and is operated by a crank, c, and connection, d. Just back of rod E is arranged a similar rod, which has an up-and-down motion imparted to it from rod E, the latter being connected by a connecting-rod, e, to one end of an arm, f, which turns on stud F, the other end of arm f being connected by a rod, g, to a projecting piece on the depressing-rod back of rod E, so that when the latter is depressed the former is elevated, and *vice versa*. G G' are the eveners, one of which works above and the other below the ends of the upper jacks B' B', the latter being fulcrumed over the top of the harnesses in the usual manner, as seen at 3. The left-hand end of evener G is hinged to a piece, h, fast on the elevating-rod E, while the other or right-hand end is connected by a hinged rod, i, to the elevating-arm H, which is also hinged to a piece, j, on rod E. The evener G' is hinged in a similar manner by one end to a piece, k, fast on the depressing-rod, while its other end is connected by a hinged rod, similar to connection i, to the depressing-arm H'. The rear ends of arms H H' are slotted out to fit pins 1 and 2 in the stand I; as indicated in the drawing. Pins 1 and 2 may be made adjustable, so that they can be moved back and forth, so that they can be set in the same vertical plane with the front edge of the woven fabric.

The operation of my invention is as follows: When the parts are in position, as shown in dark and light colors in the drawings, the warp-threads are all on a line, as shown at 4, in blue, while when the warp-threads are divided for the passage of the shuttle, the threads which form the upper and lower sheds occupy the position shown in red lines 5, 6. As heretofore constructed, so far as I am aware, looms having a large number of harnesses have not operated perfectly, or in such a manner as to raise and lower the threads in all of the harnesses so as to bring all of the threads of each shed, when made up of the threads of several harnesses, upon the same angle or inclined plane. The practical result has been that delays and breakages have been and are still constantly occurring in mills using the old-fashioned loom, resulting from the jarring motion of the harnesses and the raising and lowering of part of the threads forming a shed so as to occupy a different angle from the balance of the threads of the same shed. For instance, if the threads of one harness are too high when they form a part of the lower shed 5, then such threads are apt to be broken by the shuttle, and in turn are apt to throw the shuttle out. Again, if the threads are too low when in the same position, they are apt to chafe upon the lay, and thus cause breakages. Again, when the upper jacks B' are struck by the evener irregularly, as they are in the old style of looms, then the harnesses are apt to be jerked up and down, and the sudden and irregular movements thus given to the jacks, harnesses, and operating-bars C C, often occasion the displacement of the latter in addition to the breakages of threads, heddles, and jacks. By my improvements all of the above objections are obviated, since the depressing and elevating-arms H H' and eveners G G' act in connection and harmony with each other, while the ends of all the jacks are acted upon in such manner as to raise and lower the harnesses

in an even and easy manner. It will be noticed that the jacks which operate the back harnesses have a greater motion than the jacks which operate the front harnesses; but the threads in both the extreme back and front harnesses stand upon the same angle when the harnesses are sprung for the passage of the shuttle, as clearly indicated in red lines marked 5 and 6.

Having described my improvements in looms, what I claim as new, and of my invention, and desire to secure by Letters Patent is—

1. I claim the combination and arrangement of the hinged arms H H', hinged eveners G G', connecting-rods *i*, arm *f*, and connecting-rods *e* and *g*, substantially as set forth.
2. I also claim the combination of pins 1 and 2 with the stotted ends of arms H H', to retain the ends of said arms in proper position, and at the same time allow them to have a slight longitudinal motion, to prevent binding of the parts when the loom is in operation.

JAMES SCHOFIELD.
